UNITED STATES PATENT OFFICE.

GEORGE L. HAGY, OF SAN ANTONIO, TEXAS.

BUILDING FORM FOR CONCRETE STRUCTURES.

Application filed October 27, 1926. Serial No. 144,518.

This invention relates to an improved building form for use in erecting concrete structures, and an object of the invention is the provision of a structure wherein there is a minimum waste of material, and in which the handling of the material or parts is such that they can be used over and over again for the same purpose.

A further object of the invention relates in the provision of a structure or form which can be simply and efficiently erected with a minimum expenditure of time to form a rigid, compact and inexpensive structure or form with respect to which concrete may be quickly disposed in place.

A still further object is to provide a structure or form embodying improved inner form boards capable of being sufficiently released to permit their ready elevation to a new or higher level.

Another object is to provide a wall form including a plurality of uprights or struts arranged in pairs, with the pairs of struts arranged in a plurality of series, and means of a simple and efficient nature for tying the struts of each pair together and for tying each pair of struts of one series with a pair of struts of another series so that the several members of the form are effectively retained in proper position.

Still another object is to provide an improved form of core by means of which the wall formed by the form may be readily constructed to have vertical air passages without unduly weakening the wall structure, and whereby a minimum consumption of concrete is required for the construction of a wall of given size.

Other objects will become apparent as the nature of the invention is better understood, and the same consists in the novel form, combination and arrangement of parts hereinafter more fully described, shown in the accompanying drawings and claimed.

In the drawings, wherein like reference characters indicate corresponding parts throughout the several views,

Figure 1 is an elevational view of a building form constructed in accordance with the present invention, in place ready to erect further sections of concrete building walls on sections previously formed;

Figure 2 is an enlarged fragmentary cross section taken substantially upon line 2-2 of Figure 1;

Figure 3 is an enlarged fragmentary hori-

zontal section taken substantially upon line 3-3 of Figure 1, partly broken away;

Figure 4 is a fragmentary vertical section taken substantially upon line 4-4 of Figure 3;

Figure 5 is a plan view of the sheet metal blank from which the body of the core element is formed;

Figure 6 is a central longitudinal sectional view of the core element; and

Figure 7 is an enlarged perspective view of the wedge-shaped end section forming part of each inner form board.

The preferred embodiment of my invention, as shown in the drawings, comprises a quickly and easily assembled building form of lumber of the proper dimensions which can be erected above or in relation to a foundation wall 5 which has been previously built into the ground in any suitable manner. At intervals along the top of this wall 5 are disposed a plurality of tie rods or bolts 6 which rest on the wall and project beyond it on either side far enough to pass through 80 and connect pairs of uprights or struts 7 which are formed at their lower ends with transverse openings through which the rods 6 are passed. The uprights 7 of which there may be any number on each side of the proposed wall, are spaced from either side of the wall at a definite distance from its outer and inner faces, by means of spacing blocks 8, suitably held in place and interposed between the foundation wall and the lower 90 ends of the uprights 7 beneath the tie rods 6. This allows space for the form boards or planks 9 which are to hold the masonry or concrete in place, and also allows room for release sticks or strips of wood 10 which stand between the form boards 9 and the adjacent faces of the adjacent uprights 7. In the erection of the first wall section upon the foundation wall the boards 9 and sticks 10 rest upon the projecting portions of the 100 tie rods 6 inwardly of the uprights 7 as shown in Figure 2, but when the next succeeding sections of the wall are erected with the boards 9 raised as indicated by dotted lines in Figure 2 and with the sticks 10 correspondingly raised, said boards 9 and sticks 10 will rest upon the inwardly projecting end of cleats which are temporarily nailed to the sides of the uprights 7 as indicated by dotted lines at 11.

The uprights 7 of each pair are further connected at intervals throughout their

length by means of tie bars 12 which are temporarily nailed at their ends to the uprights so as to be capable of ready successive removal when found necessary for permitting raising of the form boards 9 as the erection of the wall progresses. Furthermore, the uprights of each pair are still further connected intermediate their ends by a further tie rod 13 which passes therethrough.

10 By the use of the tie rod 13 the uprights are effectively tied together until several sections of the wall have been erected, whereupon said rod 13 is removed and the remaining tie bars 12 thereabove are sufficient for maintaining the pairs of uprights connected.

15 In Figures 1 and 3 the form is shown in operative relation to a pair of parallel walls and a wall at right angles to and connecting said parallel walls. A series of pairs of struts 7 are arranged in operative relation to each wall, and transverse tie bars 14 connect both struts comprising a pair of one series with both struts forming a pair of a parallel series. Further, the pairs of struts 20 of each series are braced against lateral swaying by means of diagonal braces 15 which may be connected at their upper ends as at 16 to a tie bar 14 adjacent the inner strut of a pair of one series, and extend 25 downwardly and inwardly where they are attached at their lower ends to an opposed inner strut or upright of the other parallel series. It will be particularly noted that the tie bar 14, besides being nailed at its 30 ends as at 17 to a pair of uprights of one series and an opposed pair of uprights of a parallel series, is also nailed as indicated at 18 to the inner upright 7 of all of the pairs of the series at right angles to said 35 parallel series, whereby all of the uprights 40 are held in proper relative position.

When the uprights are set in place, the release sticks 10 and form boards 9 are laid against them, forming with the foundation wall or previously constructed wall section, a sort of trough which is to be filled with concrete. This trough is one board deep, and as stated above, the boards are raised as the work progresses. The form boards 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860

smaller in a downward direction both at their sides and ends so that their removal for re-use is facilitated when a section of wall has been erected. These cores are arranged in uniformly spaced relation between the form boards 9 as clearly shown in Figures 2 and 3, the spreader sticks 19 being disposed between the upper portions of the form boards at the intervals or spaces between the cores as shown. Each core body 20 is closed at its upper end by means of a top wall or plate 21 preferably formed of wood of a size to fit snugly in the upper end of the body and to be fixed therein by nailing or the like as at 22. Nailed centrally across the top wall 21 of each core is a cross piece 23, the ends of which are adapted to rest upon the upper edges of the form boards 9 and to be temporarily nailed to the latter as at 24 whereby the cores are supported in uniformly spaced relation to and between the form boards 9 as well as held against displacement from this proper position.

The body portion 20 of each core is preferably constructed of a folded sheet metal blank of the form shown in Figure 5 including a pair of side sections 25 integrally connected at adjacent side edges by an end section 26, a second end section 26^a being integral with the remaining side edge of one of the side sections 25. The free side edges of the end side section 25 and the end section 26^a are provided with flaps 27 which are adapted to be overlapped when the blank is folded into proper form, and these flaps are suitably secured together as by soldering so that a tapered tubular body is formed. Further flaps 28 are formed on the lower edges of all of the sections and provided with mitered ends so that when the sections are folded to form the tubular body the flaps 28 may be directed inwardly at right angles to the body section to form a substantially continuous inwardly directed flange 29 on the lower end of the body 20 for reinforcing the latter and thereby insuring against inward bending of the sides and ends of the core body 20 due to the pressure of the concrete thereagainst. The cores are of slightly lesser length than the depth of the form boards 9 so that the latter, when elevated and positioned to slightly overlap the previously constructed wall section at their lower edges, the lower ends of the cores will be positioned slightly in the upper ends of the air passages formed in said previously constructed wall section for insuring the air passages to be continuous vertically throughout the wall.

As shown clearly in Figures 3, 4 and 7, one end of each inner form board 9 is squared, and the adjacent end of the inner form board 9 extending at right angles thereto is mitered as at 30 so that only the

lower portion of said mitered end overlaps the adjacent squared end of the inner form board extending at right angles thereto, as indicated at 31 in Figure 4. To complete 5 or square the end of this mitered end 30 of the inner form board 9, a wedge piece 32 is employed having a tapered side 33 adapted to engage the mitered end 30 and a straight edge 34 to be positioned 10 flush with the inner surface of the inner form board provided with the adjacent squared end and extending at right angles to said inner form board 9 provided with the mitered end 30. This wedge member 15 32 is of a width at its upper end portion slightly greater than the thickness of the form board shown in Figure 4, but of a lesser width than the thickness of the form board at its lower end, and the wedge 20 member 32 is accordingly effectively supported by both boards against displacement from proper position by the outward pressure of the concrete being poured in the space between the form boards. Heretofore, the inner form boards have all been 25 provided with squared ends arranged in abutting relation, but after the concrete has been poured and allowed to set, the inner form boards have been pressed inwardly 30 so as to be in very tight engagement and thereby render the removal of the inner form boards extremely hard. However, by use of the release wedges or wedge members 32 I am enabled to quickly elevate and re- 35 move the latter so that the adjacent ends of inner form boards 9 extending at right angles to each other are relieved of firm engagement so that said inner form boards may be readily removed or elevated to the 40 next higher position. At the same time, by having the lower portion of the mitered end 30 overlapping the adjacent squared end of the adjacent inner form board 9 as at 31, said mitered end of the first inner form 45 board is effectively braced against outward bending or springing. Each wedge member 32 may be formed at its upper end with a lateral shoulder 35 adapted to rest upon the adjacent upper edge of the board 9 when in- 50 serted or lowered to proper position, and a further extension 36 may be provided above the shoulder 35 under which an instrument may be engaged for readily prying the wedge member upwardly for removal.

55 It is of course to be understood that suitable tie elements may be placed in the wall as it is being constructed for reinforcing the vertical webs formed between the cores and at the same time tying the inner and 60 outer portions of the wall connected by said webs. For this purpose, conventional substantially Z-shaped tie elements are embedded in the vertical webs from time to time as is generally well known in the art.

65 After the wall has been built to any de-

sired height, the form boards which have acted as a form to hold the wall in place during the setting of the cement up to this level, may easily be taken out or released and raised to a higher level. This is done 70 by knocking out the release sticks 10 from between the planks or form boards and the uprights so that the form boards may be raised, the release of the inner form boards being effected by removal of the wedge 75 members 32. As before stated, the cleats 11 are nailed to the uprights 7 for supporting the form boards in their new or raised positions.

The cores are detached from the form 80 boards and are then attached again after the form boards are raised to a new level, and in order to facilitate withdrawal of the cores from the cement previously allowed to set, vent openings are preferably provided 85 as at 37 in the top walls 21 of the cores. This permits the entrance of air so as to break any tendency of a vacuum being produced in the cores, thereby overcoming any 90 tendency of the cores to stick by reason of a suction effect.

In view of the above it will be apparent that I have provided a simple, compact form which can be easily and economically erected for the purpose of constructing concrete 95 structures of any desired type. It will also be seen that the erection and construction of this form requires a minimum expenditure of time and labor and the use of a minimum amount of lumber which is so 100 handled as to be capable of being repeatedly used.

Minor changes may be made without departing from the spirit and scope of the invention as claimed.

What I claim as new is:—

1. In a form for concrete walls, uprights arranged at opposite sides of the walls of an angular foundation or base, inner and outer form boards supported between said uprights with the form boards arranged in end to end angular relation, an end of one inner form board being squared, and the adjacent end of another inner form board being mitered at an outward and downward incline to partially overlap the lower part of the squared end of said one inner form board, and a release wedge engaging said mitered end and said squared end of the respective inner form boards.

2. In a form for concrete walls, uprights arranged at opposite sides of the walls of an angular foundation or base, inner and outer form boards supported between said uprights with the form boards arranged in end to end angular relation, an end of one inner form board being squared, the adjacent end of another inner form board being mitered at an outward and downward incline to partially overlap the lower part

of the squared end of said one inner form board, a release wedge engaging said mitered end and said squared end of the respective inner form boards, said wedge adapted to form a squared end finish for the mitered form board and having means to facilitate its elevation and release.

3. In a form for concrete walls, uprights arranged at opposite sides of the walls of an angular foundation or base, inner and outer form boards supported between said uprights with the form boards arranged in end to end angular relation, an end of one inner form board being squared, and the adjacent end of another inner form board being mitered

at an outward and downward incline to partially overlap the lower part of the squared end of said one inner form board, and a release wedge engaging said mitered end and said squared end of the respective inner form boards, said wedge having a shoulder at its upper end to rest upon the upper edge of the mitered form board.

4. In a concrete wall form, inner form boards having adjacent squared and mitered ends, respectively, and a release wedge engaging said squared and mitered ends.

In testimony whereof I affix my signature.

GEORGE L. HAGY.
